(57) **CLAIM**

The ornamental design for a motor vehicle has been as shown and described.

DESCRIPTION

FIG. 1 is a left side elevational view of a motor vehicle showing my new design;

FIG. 2 is a right side elevational view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a front and left side perspective view thereof;

FIG. 8 is a rear and right side perspective view thereof;

FIG. 9 is an enlarged detail area portion view of the headlight taken from circle 9 in FIG. 7, the opposite side headlight portion is a mirror image thereof;

FIG. 10 is an enlarged detail area portion view of the rear wheel taken from circle 10 in FIG. 7; the opposite side rear wheel portion is a mirror image thereof;

FIG. 11 is an enlarged detail view area portion view of the rear grill and taillight taken from circle 11 shown in FIG. 4, the opposite side rear grill and taillight portion is a mirror image thereof; and,

FIG. 12 is an enlarged detail view area portion view of the side view mirror taken from circle 12 shown in FIG. 8, the opposite side view mirror portion is a mirror image thereof. The broken lines shown in throughout the drawing views are for illustrative and environmental purposes that form no part of the claimed design.

1 Claim, 12 Drawing Sheets
